Primary Examiner — Nathan M Johnston(74) *Attorney, Agent, or Firm* — Laurence A. Greenberg; Werner H. Stemmer; Ralph E. Locher(57) **CLAIM**

The ornamental design for a liquid dispenser, as shown and described.

DESCRIPTION

FIG. 1 is a front perspective view of the liquid dispenser showing my new design;

FIG. 2 is a front elevation view thereof;

FIG. 3 is a right side elevation view thereof;

FIG. 4 is a left side elevation view thereof;

FIG. 5 is a bottom plan view thereof; and,

FIG. 6 is a top plan view thereof.

The broken lines shown in the figures represent portions of the liquid dispenser that form no part of the claimed design.
